ARTIFICIAL CANDLE

Cosimo J. Cordillo, 18 W. 5th St., New Providence, N.J.
Filed Apr. 12, 1962, Ser. No. 186,965
6 Claims. (Cl. 67—55)

The invention relates generally to artificial candles and specifically to artificial candles having both a sealable reservoir for fuel, as well as a fuel chamber.

It is an object of the invention to provide an artificial candle in which fuel is stored in a reservoir, safe from evaporation.

It is another object of the invention to provide an artificial candle with a fuel chamber that may be filled and refilled from, and emptied into a fuel reservoir.

Yet another object of the invention is to provide an artificial candle that is ready for almost immediate use after simple manipulation, and ready for deactivation and safe storage for a long period of time; this artificial candle uses an inexpensive volatile fuel.

These objects and advantages as well as other objects and advantages may be attained by the device, shown by way of illustration in the drawings in which:

FIGURE 1 is an elevational view of an artificial candle inserted in a candle holder;

FIGURE 2 is a vertical sectional view thereof;

FIGURE 3 is a cross-sectional view taken on the line 3—3 in FIGURE 2, looking in the direction of the arrows;

FIGURE 4 is a perspective view of the insert;

FIGURE 5 is a perspective view of the top of the second or lower part of the valve stem.

Artificial candles are well-known. Those using liquid fuel require frequent refueling due to the evaporation of the fuel. The present artificial candle has a sealed reservoir from which fuel does not evaporate but is always ready for delivery to a fuel chamber. After the candle has been used, any remaining fuel may be returned to the reservoir, rather than being permitted to remain in the fuel chamber where it may evaporate. A large reserve of fuel may always be maintained on hand for delivery to the fuel chamber.

Referring now to the drawings in detail, my artificial candle has an elongated tapered shell 11 shaped generally like the conventional wax candle. At the top, there is a threaded internal shoulder 12. A conical nozzle 13 having an axial bore 14 is provided for the top of the shell. The nozzle 13 has an externally threaded tubular enlargement 15. The axial bore 14 has, at its lower end 16, an internal diameter somewhat larger than a wick 17 which fits the axial bore 14. The wick-cover 18 of felt surrounds the wick 17 and fits into the axial bore 14. The threaded tubular enlargement 15 engages the threaded shoulder 12. The nozzle is also provided with an annular channel 19. The top of the shell is provided with a complementary annular rib 20 which engages a seal-ring 21 in the channel to prevent leakage at the juncture of the nozzle 13 and shell 11.

An internal shoulder 22 is formed in the shell, either integral therewith or as a separate insert, press fitted to engage the tapering interior wall of the shell, and to define a valve seat. The area above the shoulder is the fuel chamber 23, while the area below it is the fuel reservoir 24. The shoulder has two opposing, integral legs 25 extending downwardly and connected together by a cross-member or integral strap 26. The strap 26 has a central bore 27. Near the top of the shoulder, there is a cutout portion or annular seat 28 on which is positioned an O-ring 29.

An inverted conical valve 30 engages the O-ring 29 and seals the upper fuel chamber 23 from lower fuel reservoir 24. A valve stem 31 extends downwardly from the valve,

2

through the strap 26. The lower end 32 of the valve stem has a lesser cross-sectional area than the upper end. A second part 33 of the valve stem has a central bore 34 and receives the lower end 32 of the first part of the valve stem. The top of the second part 33 of the valve stem has lateral enlargements 35. A spring 36 carried by the first part of the valve stem 31 and seated on the lateral enlargements engages the strap 26 and normally urges the valve into sealing engagement with the valve seat 28.

The lower end of the shell 11 is internally threaded. An externally threaded end-cap 37 closes the end of the shell. An external flange 38 on the end-cap with a channel above the flange carries an O-ring 39 to insure against leakage of fuel from the reservoir. The end-cap 37 has a central bore of varying dimensions. The top portion 40 of the central bore in the end-cap terminates in a shoulder which defines the start of a narrower second portion 41 of the central bore. A flexible seal 42 is seated on this shoulder. Below the second portion is a third narrower portion 43 of the bore. A push rod 45 with a mushroomed-head 46 is seated in the second portion of the bore. In the first portion 40 of the bore, a seal retainer 47 holds the seal in place and serves to center the second part 33 of the valve stem on the seal 42.

The operation of the artificial candle is as follows. The end cap 37 is removed and the fuel reservoir 24 is filled with fuel. The cap 37 is replaced. When it is desired to fill the fuel chamber 23, the candle is inverted and the push-rod 45 end is pressed. This engages the seal 42 and domes it upwardly. It likewise moves the valve stem 31, 33 to overcome the spring 36 which unseats the valve 30, thereby permitting fuel to leave the reservoir 24 and enter the fuel chamber 23. After the candle is used, and without again inverting it, pressure on the push-rod 45 will allow the residual fuel in the fuel chamber 23 to drain back into the reservoir 24, where it is safe from evaporation until its use is again called for.

The fuel for the artificial candle may be any of the well-known hydro-carbon or mineral oils, such as the readily available cigarette lighter fuel. The shell 11 may be made of metal, such as aluminum, or of any of the well-known plastics which in texture and color may resemble white or colored wax. The nozzle 13 is preferably made of metal, although, ceramic or plastic materials may also be used. The insert, the valve, and the valve stem and pusher may be made of metal or plastic, or any material relatively impervious to fuels such as might be used.

The foregoing description is merely intended to illustrate an embodiment of the invention. The component parts have been shown and described. They each may have substitutes which may perform a substantially similar function; such substitutes may be known as proper substitutes for the said components and may have actually been known or invented before the present invention; these substitutes are contemplated as being within the scope of the appended claims, although they are not specifically catalogued herein.

60 What is claimed:

1. An artificial candle comprising:
  - (a) an elongated shell shaped in the form of a candle,
  - (b) a shoulder in the shell defining a valve-seat and delineating a top fuel chamber and a bottom fuel reservoir,
  - (c) a strap extending across the valve-seat and having a central bore to guide a valve stem,
  - (d) a valve-stem in the central bore of the strap,
  - (e) a valve on the valve stem and engageable with the valve seat,
  - (f) a spring engaged with the valve stem normally

- urging the valve into sealing engagement with the valve-seat,
- (g) a nozzle with an axial bore at the top of the shell,
- (h) a wick in the axial bore of the nozzle,
- (i) a refueling plug engageable and disengageable with the bottom of the shell, the plug having a central passage tapered in the direction of the end opposite the shell and shaped in the form of the bottom of a candle,
- (j) a shoulder in the central-passage in the refueling plug,
- (k) a push-rod in the central passage,
- (l) a head on the push-rod seated on the shoulder in the central-passage,
- (m) a seal in the central passage above the head of the push rod,
- (n) an annular retainer for the seal engaged with the refueling plug in the central passage thereof,
- (o) the valve-stem engaged with the seal in opposition to the head of push rod.
2. An artificial candle comprising:
- (a) an elongated shell shaped in the form of a candle,
- (b) a refueling plug engageable and disengageable with the bottom of the shell shaped in the form of the bottom of a candle and the plug having a central passage,
- (c) a shoulder in the central passage in the refueling plug,
- (d) a push rod in the central passage,
- (e) a head on the push-rod seated on the shoulder in the central passage,
- (f) a seal positioned in the passage above the head on the push-rod,
- (g) an annular retainer for the seal engaged with the refueling plug in the central passage thereof,
- (h) a valve-stem engaged with the seal in opposition to the head of the push rod.
3. An artificial candle comprising:
- (a) an elongated shell shaped in the form of a candle,
- (b) a refueling plug engageable and disengageable with the bottom of the shell shaped in the form of the bottom of a candle and the plug having a central passage,
- (c) a shoulder in the central passage in the refueling plug,
- (d) a push rod in the central passage,
- (e) a head on the push-rod seated on the shoulder in the central passage,
- (f) a seal positioned in the passage above the head on the push-rod,
- (g) an annular retainer for the seal engaged with the refueling plug in the central passage thereof.
4. An artificial candle comprising:
- (a) an elongated shell shaped in the form of a candle,
- (b) a top fuel chamber in the shell,
- (c) a bottom fuel reservoir in the shell,
- (d) a removable refueling plug at the bottom of the shell shaped in the form of the bottom of a candle and the plug having a central passage,

- 4
- (e) a flexible seal in the central passage in the refueling plug,
- (f) a valve sealing the reservoir and chamber from each other,
- (g) a spring normally urging the valve to seal the chamber from the reservoir,
- (h) a valve stem on the valve extending to the flexible seal.
5. An artificial candle comprising:
- (a) an elongated shell shaped in the form of a candle along its entire length,
- (b) a top fuel chamber in the shell,
- (c) a bottom fuel reservoir in the shell,
- (d) a deformable seal at the bottom of the fuel reservoir, the seal being deformable from without the shell,
- (e) a spring-loaded valve in the shell normally sealing the fuel chamber from the fuel reservoir;
- (f) a valve stem extending from the valve in the shell to the deformable seal at the bottom of the fuel reservoir whereby deformation of the seal from without the shell moves the valve stem to unseat the valve.
6. An artificial candle comprising:
- (a) an elongated shell shaped in the form of a candle;
- (b) a valve seat in the shell intermediate its ends defining a top fuel chamber and a bottom fuel reservoir;
- (c) a valve engageable with the valve seat;
- (d) a valve stem on the valve extending into the bottom fuel reservoir;
- (e) resilient means engaged with the valve stem normally urging the valve into sealing engagement with the valve seat;
- (f) a removable refueling plug at the bottom of the shell shaped in the form of the bottom of a candle;
- (g) a flexible seal positioned between the refueling plug and the bottom fuel reservoir, and
- (h) means in the refueling plug to deform the seal in the direction of the valve stem, the valve stem engaging the seal upon deformation unseating the valve from the valve seat.
